GRINDING AND POLISHING MACHINE

Rufus W. Fuller, Deerfield, Mass., assignor to
 Production Machine Company, Greenfield,
 Mass., a corporation of Massachusetts

Application December 31, 1936, Serial No. 118,613

15 Claims. (Cl. 51—79)

The present invention relates to grinding and polishing machines and more particularly to supplementary work supporting and feeding mechanism for the same.

5 The preferred embodiment of the invention represents an improvement on the work supporting mechanism disclosed in the patent to R. W. Fuller, No. 1,900,984, dated March 14, 1933, and is particularly, though by no means exclusively, adapted 10 for use in conjunction with grinding and polishing machines of the centerless type, of which the machine illustrated in the patent to R. W. Fuller, No. 1,421,205, dated June 22, 1922, is an example. Such machines are commonly used for grinding 15 and polishing cylindrical work, which is fed through the machine and past the abrasive member with a combined rotational and axial movement, this movement being imparted to the work by a feed roll or endless belt which also holds the 20 work against the abrasive belt or wheel. The rate of feed of the work is dependent upon the inclination of the work feeding roll or belt with respect to the axis of the work.

In order to grind or polish long lengths of rod 25 or tubing, it is necessary that the material be supported at each side of the machine. The supporting mechanism described in Patent No. 1,900,984, while satisfactory for handling small rods and tubing, has not proved adequate where long 30 lengths of comparatively heavy cylindrical work must be ground or polished. Since the only mechanism there provided for rotating and feeding the work is the feed belt of the machine, it is evident that the work is in non-rotating condition 35 when it first comes into contact with the feed belt and grinding wheel or abrasive belt. Due to the inertia of the work, appreciable time is required before the work revolves with the same surface speed as that of the feed belt, with the result that 40 a flat place is frequently ground in the work. In some cases the work may fail to revolve at all, due to friction between the work and the guide rolls, which do not revolve with rotational movement of 45 the work, but only when the work moves in an axial direction.

With a view to improving the side work support of Patent No. 1,900,984 above referred to, the principal object of the present invention is to provide a side work support for grinding machines and the like having means for imparting directly to the work both rotational and axial movements to supplement the feeding mechanism of the machine, whereby cylindrical work of substantial weight and length may be satisfactorily ground or 50 polished.

A further object of the invention is to provide a side work support for grinding machines and the like having a plurality of work engaging and work guiding rolls, all of which may be similarly inclined axially with respect to the axis of the work 5 to any desired extent within the range provided, whereby combined rotational and axial movements may be imparted to the work with a minimum of rubbing friction between work and rolls.

Another object of the invention is to provide a 10 side work support for grinding machines and the like having power-driven work supporting and work guiding means capable of adjustment to permit the support to accommodate various sizes of work while maintaining at all times one side of the 15 work in the same vertical plane and the axis of the work in the same horizontal plane.

With these objects in view, the present invention comprises a side work support for supporting and guiding long cylindrical work while imparting 20 both rotational and axial movements thereto by means of sets of work guiding and power-driven work supporting rolls having provision for axial inclination with respect to the axis of the work. The work supporting rolls are also arranged for 25 combined vertical and horizontal adjustment, and one set of guide rolls for horizontal adjustment, so that work of various diameters may be accommodated while maintaining the axis of the work in the same horizontal plane. Means are also provided for simultaneously adjusting the angle of 30 inclination of both work supporting and guiding rolls to secure any desired rate of feed.

In the drawings illustrating the preferred embodiment of the invention, Fig. 1 is a top plan 35 view of the side work support; Fig. 2 is a view in front elevation of the same; Fig. 3 is an end elevation, on an enlarged scale, looking from the right in Fig. 2; Fig. 4 is a sectional detail, on a still larger scale, of the work contacting roll and 40 mounting therefor; and Fig. 5 is an end view of the same.

The centerless grinding and polishing machine of the type illustrated in Patent No. 1,421,205 above referred to comprises briefly an abrasive-coated endless belt traveling at high speed in a vertical plane, with a feed roll or belt, which engages the work on the opposite side of the abrasive belt, traveling at relative low speed. The feed roll or belt has provision not only for bodily movement toward and away from the abrasive belt to accommodate work of different diameters, but also for various inclinations with respect to the axis of the work for feeding the work axially at different 50 speeds as the latter is rotated by the frame. A 55

fixed work support between the abrasive and feed rolls supports the rotating work in proper position.

While only a single work support is illustrated and described herein, it is to be understood that 5 the machine of the type above described would ordinarily be provided with two side work supports, one at each side of the grinding or polishing machine proper, in order that the work might be adequately supported while the grinding or polishing 10 operation is being performed, and also to assist in feeding the work up to and away from the machine before and after such operation takes place.

While the work support of the drawings is 15 designed for use in connection with a centerless grinding or polishing machine such as shown in Fuller Patent No. 1,900,984, above referred to, it is preferably constructed as a separate unit detached from the machine proper but positioned adjacent thereto. The framework of the 20 side work support upon which the various work guiding and supporting instrumentalities and their associated parts are mounted, comprises end stands or frames 16 to which are secured 25 the longitudinal angular members 18, 20, 22, each constituting a bed for a set of work contacting rolls. The rear member 18 is rigidly secured to the end frames 16, being bolted to spacer blocks 24.

30 The front bed member 20 is arranged for transverse movement toward and away from the work, being mounted on carriages 26 which slidably engage guideways 28 on the end frames 16. The bed is adjusted on said guideways by 35 means of racks and pinions, the racks 30 being secured to the carriages 26, while the pinions 32 are arranged on a single shaft 34 journaled in bearings 38 in the end frames 16. The shaft 34 is rotated by means of a suitable tool which 40 is inserted in holes 40 spaced about the periphery of an adjusting disk 42 secured to the shaft.

The bed 22, upon which the work supporting rolls are mounted, is arranged for simultaneous 45 vertical and horizontal adjustment, so that the center lines of work of various diameters may all lie in the same horizontal plane, while maintaining the side of the work which is engaged by the abrasive means always in the same vertical plane, thereby eliminating the need for adjusting the position of the abrasive belt or wheel 50 for each size of work. The bed 22 is secured to brackets 43 formed on sleeves 44 which are arranged to slide on cylindrical guideways 46 attached to each of the end frames 16. A shaft 55 48 journaled in bearings in the sleeves 44 has pinions thereon which mesh with rack teeth on the guideways 46. The shaft is rotated in a counter-clockwise direction to raise the brackets and bed by means of a handle 50 which is loosely 60 mounted in the shaft and adapted to be connected thereto by suitable ratchet mechanism indicated generally at 52, a pawl 54 which engages a ratchet wheel 56 fixed on the shaft preventing rotation in reverse direction except when 65 the pawl is lifted.

The work supporting rolls 58 which are mounted on the bed 22 are pivotally mounted as illustrated in Fig. 4 to permit their axis to be inclined with respect to the axis of the work for feeding 70 the work in an axial direction as the work rotates. The rolls are provided with a covering of rubber, leather, felt, or the like, depending on the nature of the work to be handled, and one side of the roll surface is bevelled as at 61 75 to provide smooth engagement with the work

as it moves axially into contact with the rolls. The rolls 58 are keyed to short shafts 62 journaled in bearings 64 in the arms of the roll frames 66, which are pivotally mounted on sub-bases 68. The sub-bases are attached to the 5 bed 22 by means of studs 70, the set screws 71 affording adjustment to insure steadiness in case the surface of the bed is irregular.

The roll frames 66 are rotatably held in position on the annular faces or flanges 72 of the 10 sub-bases 68 by means of a hold-down member 73 having a cylindrical and a shoulder portion 74 and 75 respectively for engaging the roll frame, and a threaded portion 76 which screws into a tapped hole in the sub-base. The members 73 are provided with a recess 77 shaped to receive a tool by which they may be rotated to adjust the pivotal clearance or tightness of the bearing of the frames between the hold-down members and the sub-bases. After the desired 20 adjustment has been secured the parts may be locked in position by tightening the stud 78 which passes through the bed 22 into the tapped hole on the hold-down member 73.

The work supporting rolls are simultaneously 25 adjusted for uniform inclination with respect to the axis of the work by means of a longitudinally extending strip or bar 79 pivotally connected to arms 80 projecting from each of the roll frames 66. A pointer 81 on the bed or support 22 and a scale 82 on the bar facilitates 30 accurate adjustment of the rolls to the desired angle of inclination.

The rolls are locked in the desired angular 35 position by means of a set screw 83 in one of the roll frames 66, the end of the screw engaging the cylindrical portion 74 of the hold-down member 73.

The work supporting rolls are rotated from 40 a gear box 84 mounted on the support 22, universal joint 85 and splined telescoping joints 86 in the connecting shafts 88 permitting the transmission of power irrespective of the axial inclination of the rolls. The gear box is driven by a multiple V-belt 90 from a countershaft 92 45 journaled in bearings 94 mounted on the end frames 16. An idler pulley 96 on the end of arm 98 pivotally attached to the bed 22 maintains suitable tension in the belt during all positions of the bed. The countershaft is driven 50 from a suitable source of power, not illustrated.

The work guiding rolls 100 are mounted on the angular bed members 18 and 20 in roll frames 102 substantially similar to the work supporting roll frames 66, with the added feature of integral webs 104 which aid in guiding the work into proper position as it is lowered into the support. The rolls are somewhat smaller in diameter than the work supporting rolls 58, since they are merely idler rolls, for guiding 60 the work. The guide rolls of each set are angularly adjusted to secure the desired feed by connecting strips or bars 106, scales 108 on the strips cooperating with fixed pointers 110 in the support to aid in setting the idler rolls to the same axial inclination as the work supporting rolls, and a set screw locking the roll frames in the desired angular adjustment in the same manner as with the feed rolls.

In the use of the improved side work support, 70 this will be positioned on the work supply side of the grinding or polishing machine (preferably with a second similar support on the work discharge side) in proper axial alignment therewith.

The diameter of the work being determined, the preliminary adjustment of the work supporting rolls 58 and the movable work guiding rolls 100 will be made. For the work supporting rolls this is accomplished by means of the handle 59 and shaft 48 through the pinions and racks, causing the mountings for the rolls to slide up or down on the inclined guideways 46 according to whether smaller or larger sizes of work are to be fed. The parts are held in the desired position against their own weight by the locking pawl 54. The movable work guiding rolls are then adjusted toward and from the fixed rolls by the rack and gear connection from the rotating shaft 34, by means of the wrench or tool fitted on the disk 42.

The sets of rolls now being properly spaced relatively to one another, the rolls are angularly adjusted for the desired rate of feed. If the grinding machine proper has a feed, the rate of feed of the side support will be adjusted to coincide therewith. The work feeding rolls are adjusted simultaneously by moving the bar or rod 79 manually the proper amount, the set screw 83 being first loosened to permit such movement and then being tightened to hold the parts securely in the desired angular position. The work guiding rolls are similarly adjusted, the several scales and pointers enabling the operator to secure uniform angularity with a minimum of effort.

The feed rolls are next set in operation from the source of power at the proper rotational speed as determined by the gear box in accordance with the requirements of the work.

Work is now supplied to the support, conveniently by laying it on the work supporting and feed rolls and between the guide rolls, the inclined webs 104 above the latter rolls guiding the work as it is lowered into position. As soon as the work contacts the positively driven feed rolls, it is set in rotation and at the same time is advanced to the grinding and polishing machine proper. Thus it comes rotating to the grinding and polishing instrumentalities and the formation of flats or other imperfections is prevented.

If desired, work may be fed continuously through the machine with a minimum of effort and skill on the part of the operator, it being necessary only to keep the work support supplied with lengths of work which contact with at least two of the feed rolls. The feeding of the work to, past, and from the working instrumentalities is wholly automatic.

Due to the use of positively driven feed rolls, long and heavy work will be given a more uniform and steady rotation at the desired speed than can be secured by the use of a single feed roll or belt. The work resting on the driven feed rolls by its own weight automatically secures the proper contact for rotation, yet without excessive pressure between the parts. By providing for adjustment of the angularity of the rolls, varying rates of feed can be obtained as required by the various characters of the work.

While the side support constituting the invention has been described in conjunction with a centerless grinding and polishing machine, it is to be understood that the invention is not limited to use with such machines, but is intended and adapted for use with any machine which operates on long cylindrical work which is subjected to simultaneous rotational and axial movements in the course of the working operation.

Nor is the present invention limited to the

particular forms and arrangements of parts herein shown and described, for these may be varied and modified and other forms and arrangements employed within the scope of the appended claims.

The nature and scope of the invention having thus been described, what is claimed is:

1. A side work support for grinding machines and the like having a frame provided with inclined ways, guides movable on the ways, a work supporting and feeding roll carried by the guides, a driven pulley supported on the guides, a driving pulley mounted in fixed position on the frame, the movement of the driven pulley and supporting guides on the ways being approximately normal to the plane of the axes of the pulleys.

2. A side work support for grinding machines and the like having a frame provided with inclined ways, guides movable on the ways, a supporting and feeding roll carried by the guides, a driven pulley supported on the guides, a driving pulley mounted in fixed position on the frame, the movement of the driven pulley and supporting guides on the ways being approximately normal to the plane of the axes of the pulleys, a belt connection between the driving and driven pulleys, and a pivoted weighted belt tightener to maintain substantial uniform belt tension for varying positions of the driven pulley.

3. A side work support for grinding machines and the like having a frame provided with inclined ways, guides movable on the ways, a supporting bed carried by the guides, a set of work supporting and feeding rolls carried by the bed, and means comprising cooperating rack and pinion for adjusting the guides on the ways.

4. A side work support for grinding machines and the like having a frame provided with inclined ways, guides movable on the ways, a supporting bed carried by the guides, a set of work supporting and feeding rolls carried by the bed, means comprising cooperating rack and pinion for adjusting the guide on the ways, a handle for actuating the pinion, and a ratchet and pawl device for holding the bed in adjusted position.

5. A side work support for grinding machines and the like having a supporting bed, a plurality of spaced work engaging rolls, supports for said rolls pivotally mounted on the bed to provide for the angular axial adjustment of the rolls with respect to the axis of the work, and means including arms carried by the roll supports and connections between said arms for simultaneously adjusting the roll supports angularly.

6. A side work support for grinding machines and the like having a supporting bed for supporting a plurality of spaced work engaging rolls carried thereby, means for securing the rolls to the bed having provision for angular adjustment of the rolls with respect to the axis of the work, means for simultaneously adjusting said rolls angularly, and cooperating pointer and scale, one fixed and the other movable with the angular movement of the rolls to facilitate said angular adjustment.

7. A side work support for grinding machines and the like comprising a frame having transverse ways therein, guides movable in the ways, a supporting bed fixed upon the frame, a second supporting bed mounted on the guides, sets of spaced work engaging rolls carried by said beds, and means for moving the guides and bed carried thereby toward and from the fixed bed.

8. A side work support for grinding machines and the like having a frame provided with in-

- clined ways, guides movable on the ways, a supporting bed carried by the guides, a set of work supporting and feeding rolls carried by the bed, means comprising cooperating rack and pinion 5 for adjusting the guides on the ways, and means for actuating the supporting and feeding rolls independently of the work.
9. A side work support for grinding machines and the like having a bed, a plurality of spaced 10 work engaging rolls, roll supports each having a bore, a base for each roll support provided with a threaded opening and secured to the bed, a member extending through the bore for pivotally securing the roll support to the base, said member having a threaded portion adapted to engage the threaded opening in the base whereby said member may be rotated to adjust the pivotal clearance between roll support and base, and threaded means for securing the member 15 against rotation relative to the base.
10. A side work support for grinding machines and the like having a bed, a plurality of spaced work engaging rolls, roll supports each having a bore, a base for each support provided with a 20 threaded opening and secured to the bed, a member extending through the bore for pivotally securing the roll support to the base, said member having a threaded portion adapted to engage the threaded opening in the base to afford adjustment of pivotal clearance between roll support and base by rotation of said member, means for securing the member against rotation in the 25 base, and threaded means in the roll support adapted to engage the member for securing the roll support against rotation relative to the base.
11. A side work support for grinding machines and the like having a plurality of spaced rolls bodily adjustable to accommodate work of various diameters and angularly adjustable with 30 respect to the axis of the work independently of their bodily adjustment to vary the rate of feed imparted to the work, and means for rotating the rolls from a source of power under their varying bodily and angular adjustments, said means 35 including a telescoping shaft and universal joints for rotating one of said rolls from another of said rolls.
12. A side work support for grinding machines and the like for supporting rotating work independently of its diameter with its periphery tangent to a fixed plane including the point of operation of the machine on the work, said support comprising a set of spaced work engaging idler rolls fixed in position tangent to said plane and 40 on the opposite side thereof from the work, a second set of spaced work engaging idler rolls

bodily movable toward and away from the fixed set of rolls, and a third set of work engaging rolls bodily movable toward and away from the fixed rolls, the rolls of the third set being driven from a source of power to rotate the work and angularly adjustable with respect to the axis of the work independently of their bodily adjustment to vary the rate of feed imparted to the work. 5

13. A side work support for grinding machines and the like adapted to support rotating work 10 with the periphery thereof tangent to a fixed plane which includes the point of operation of the machine on the work, said support comprising a set of work engaging idler guiding rolls fixed in position at one side of the work, a second set 15 of work engaging idler guiding rolls movable toward and away from the first set of rolls in a plane substantially normal to the first plane, and a third set of work engaging rolls adjustably positioned beneath the work to support the same 20 irrespective of its diameter with its axis in the same plane normal to the first plane, the rolls of the three sets being angularly adjustable with respect to the axis of the work to vary the rate of feed, and the rolls of the third set being driven 25 from a source of power to rotate the work.

14. A side work support for grinding machines and the like for supporting rotating work independently of its diameter with its periphery tangent to a fixed plane, said support comprising 30 a set of spaced work-engaging rolls positioned tangent to said fixed plane on the opposite side thereof from the work, a second set of spaced work-engaging rolls bodily movable toward and from the first set, and a third set of work- 35 engaging rolls bodily adjustable with respect to the first set of rolls, the rolls of the three sets being rotatable in planes transverse to the axis of the work, and the rolls of one of the sets being angularly adjustable with respect to the axis of 40 the work to vary the rate of feed thereof.

15. A side work support for grinding machines and the like for supporting rotating work independently of its diameter with its periphery tangent to a fixed plane, said support comprising 45 a set of spaced work-engaging rolls positioned tangent to said fixed plane on the opposite side thereof from the work, a second set of spaced work-engaging rolls bodily movable toward and from the first set, and a third set of work- 50 engaging rolls bodily adjustable with respect to the first set of rolls, the rolls of the three sets being angularly adjustable with respect to the axis of the work to vary the rate of feed imparted thereto. 55

RUFUS W. FULLER.
